UNITED STATES PATENT OFFICE.

PATRICK FEENEY, OF WALKER'S MILLS, PENNSYLVANIA.

DESIGN FOR A REAMER-DRILL.

SPECIFICATION forming part of Design No. 27,475, dated August 3, 1897.

Application filed June 9, 1897. Serial No. 640,072. Term of patent 14 years.

To all whom it may concern:

Be it known that I, PATRICK FEENEY, a citizen of the United States of America, residing at Walker's Mills, in the county of Allegheny and State of Pennsylvania, have invented a certain new and original Design for Reamer-Drills, of which the following is a specification, reference being had therein to the accompanying drawings.

10 This invention relates to a certain new and original design in a reamer, of which the following is a specification, reference being had to the accompanying drawings, in which—

Figure 1 is a perspective view of my design. Fig. 2 is a cross-sectional view of the same.

As shown in the drawings, the leading feature of my design resides in the bit of the reamer, which is formed with a flat side *a*, 20 which is on a relative plane with the shank *b*. The bit resembles a triangle in general outline, but is formed with two convex sides *c* and

d and the one straight side *a*. The three corners *a'* *a''* *a'''* thus formed project slightly beyond the plane of the shank, which is made 25 more pronounced by chamfering the shank, as shown at *e*, at its intersection with the bit proper.

What I claim is—

1. The design of reamer as herein shown 30 and described.

2. The design for a reamer, having a bit approximately resembling a triangle, substantially as shown and described.

3. The design for a reamer, having a bit 35 formed with two concave sides, the points of the bit projecting beyond the shank, substantially as shown and described.

In testimony whereof I affix my signature in presence of two witnesses.

PATRICK FEENEY.
